UNITED STATES PATENT OFFICE.

EUGENE L. KEYES, OF BOSTON, MASSACHUSETTS, ASSIGNOR TO UNITED SHOE MACHINERY COMPANY, OF PATERSON, NEW JERSEY, A CORPORATION OF NEW JERSEY.

TRIMMING-MACHINE.

1,130,742.

Specification of Letters Patent.

Patented Mar. 9, 1915.

Application filed April 7, 1913. Serial No. 759,421.

To all whom it may concern:

Be it known that I, EUGENE L. KEYES, a citizen of the United States, residing at Boston, in the county of Suffolk and State of 5 Massachusetts, have invented certain Improvements in Trimming-Machines, of which the following description, in connection with the accompanying drawings, is a specification, like reference characters on 10 the drawings indicating like parts in the several figures.

This invention relates to machines for trimming or shaping blanks formed from sheet material, and one important object is 15 to effect an improvement in that class of machines that operate to scarf or bevel the face of the blank, by providing means to regulate the beveling operation so as to insure a cut of constant depth however the 20 thickness of the work may vary.

In a more particular aspect the invention contemplates an improvement in machines that operate to trim the edges of the work and simultaneously to scarf or bevel the 25 face of the work at the edges. Machines of this type usually include an edge trimming cutter and a second or beveling cutter.

This invention, in a preferred embodiment, comprises means to effect relative adjustment of the work and the beveling cutter without disturbing the operative relation of the work to the edge trimming cutter, through the operation of a member that contacts with the work and is movable in 30 proportion to variations in the thickness of the latter. The relative positions of the work and the beveling cutter will depend, therefore, upon the thickness of the blank, and that face of the work which is to be 35 beveled will be presented constantly in the same position in relation to the cutter through the operation of the contact member.

The invention contemplates also provision 40 for varying at will the normal relation of the beveling means to the regulating means so as to change the depth of the bevel.

A further particular object of the invention is to provide means for beveling or 45 scarfing the face of a welt insole at the heel seat after the insole has been attached to the last. In the manufacture of this type of shoe it is often found desirable to scarf the 50 face of the insole at the edges of the heel seat so as to approximate the thickness of

the channeled portion of the insole edge, and thereby insure a better fit for the counter and other portions of the upper when assembled upon the insole in the lasting operation. Since it is a common practice, however, to provide an insole that shall be somewhat longer than the last after the tempering and channeling operations, and then after attachment of the insole to the last to trim off that portion which projects beyond the last at the heel end, it is obvious that the scarfing operation cannot well be performed prior to the operation of trimming off the surplus projecting material. By this invention I have provided means whereby the scarfing operation may be performed at this stage in the manufacture of the shoe in a rapid and effective manner. In this aspect the invention contemplates more particularly an improvement in a machine that forms the subject-matter of my prior Patent 1,076,431, granted Oct. 21, 1913, the purpose of which is to trim off the projecting portion of the insole at the heel end after attachment of the insole to the last; and an important feature of the invention resides in means whereby both the operations referred to may be performed simultaneously on a single machine, thereby eliminating the time and expense of a subsequent scarfing operation. At the same time, the controlling features previously noted permit the formation of a bevel of any depth desired, thicknesses of work without further attention of a bevel of constant depth for different and after adjustment insure the formation 90 on the part of the operator.

A further improvement in my prior machine which I contemplate as a feature of this invention resides in means for determining or limiting the movement of the last and its attached insole when presented to the action of the cutter. This feature comprises means suitably positioned to limit movement of the forepart of the last toward the rear of the machine as the last is mounted to turn upon its support, whereby to insure such a movement of the last in consequence of movement of the support when the sides of the heel seat near the shank are presented to the action of the cutter that trimming too far inward toward the shank and abruptly beginning or ending the trimming operation at definite points near the shank, with consequent formation 100 105 110

of ridges at the sides of the insole, are avoided. This is a feature of particular utility in cases where the insole is wider than necessary at the shank portion or is 5 unevenly placed upon the last so that portions project beyond the bottom of the last at the shank.

Other features and objects of the invention will be noted in the following detailed 10 description and pointed out in the claims.

In the drawings, Figure 1 is a view in elevation of a machine that comprises a preferred embodiment of the invention, portions of the frame of the machine being 15 broken away. Fig. 2 is a section through portions of the cutters and the guiding and regulating means, showing also the operative position of the work. Fig. 3 is a detail view illustrating more clearly the operative 20 relation of a last and insole to the guiding member and the cutters.

The frame 2 of the machine supports a rotary shaft 4 upon the forward end of which is secured a rotary edge-trimming 25 cutter 6. The cutter is held in place by means of an expansion bushing 8 and a plate 10 which is secured upon the end of the shaft by a screw 12 so as to maintain the bushing in expanded condition against the 30 cutter. The plate 10 is circular in form and extends peripherally somewhat beyond the adjacent portions of the cutter teeth, thereby providing a guide that assists in maintaining the work in operative relation to 35 the cutter.

Pivottally supported upon a stationary bracket 14 so as to swing toward or away from the cutter in a plane substantially parallel to the cutter shaft is a guide carrying head 16. This head may be swung upward to afford access to the cutter, but is secured in normal or operative position by means of a plate 18 that slides through one 40 side thereof and engages beneath the head 45 of a bolt 20 that is threaded into a portion of the bracket 14. The head 16 has inclined guideways to receive a guide or abutment member 22 that has a guiding face or shoulder 24 and a lip 26 that projects slightly 50 beyond said face along the inner edge of the guide. It will be noted that the inner face of the member 22 is recessed to receive 55 the plate 10 at the forward end of the cutter so that the lip 26 is close to the periphery of the cutter. The member 22 may be adjusted radially of the cutter by means of an 60 adjusting screw 28 that extends through a portion of the head and is held from movement therethrough, but has threaded engagement with the guide member. The preferred embodiment illustrated comprises a machine for operating upon the heel portion of a Goodyear welt insole after the latter has been attached to the last, and the 65 face 24 provides means upon which to posi-

tion the side surfaces of the last, while the lip 26, projecting between the tread face of the last and the insole, serves to position the last axially of the cutter and provides an abutment or rest for the under side of the 70 work during the cutting operation. The member 26 serves also to guard the edge trimming cutter from contact with the metal anvil plate with which the heel end of a last is usually provided. Obviously adjustment 75 of the member 22 serves to vary the distance of the last from the axis of the cutter and therefore the depth of operation of the cutter with respect to the last.

In order to hold the insole firmly during 80 the cutting operation, a presser member 30 is arranged to contact yieldably with the outer face of the work close to the periphery of the cutter. The member 30 is formed with a straight portion that is arranged to 85 slide in a guideway 32 formed between adjacent faces of a portion of the head 16 and a plate 34 secured thereto. The guideway 32 is inclined in a direction substantially parallel to the periphery of the cutter 6. 90 The presser member is urged toward the work by a spring 36 and a plunger 38 that operate in a socket formed in a portion of the head 16, the plunger bearing against the rear side of the presser member. The extent of forward movement of the presser member is limited and may be varied by means of an adjusting screw 40 threaded through an angular portion of the member 30 at the rear of the guideway, the end of 100 said screw bearing against the head.

As a means for scarfing or beveling the face of the work simultaneously with the trimming operation I have provided a second or beveling cutter 42 concentric with 105 the cutter 6 and connected by means of a bayonet joint to a sleeve 44 which is mounted upon the shaft so as to be axially adjustable thereon. The teeth of the cutter 42 are arranged to project normally between the 110 teeth of the cutter 6 and are suitably inclined to give the desired degree of bevel. A spring 46 bears at one end against a collar on the shaft and at its other end is seated in a socket in the sleeve 44 so as to 115 urge the sleeve and the cutter 42 normally toward the work.

Pivottally mounted on the same axis as the head 16 is an arm 48 that has a forked portion 50 partly embracing the sleeve 44 120 and providing means for supporting pivottally segment pieces 52 that are loosely seated in an annular recess in the periphery of the sleeve. The arm 48 has also a projecting portion 54 that extends to a point opposite the rear end of an extension 56 of the plunger 38 and is provided with an adjusting screw 58 that bears upon the end of the extension 56.

With the mechanism described it will be 130

obvious that there is a dependent operative relation between the position of the beveling cutter 42 and the position of the presser member 30. Both the cutter and the presser member are urged toward their limits of movement in the direction of the work and the lip or abutment 26, and the extent of movement permitted the beveling cutter in this direction depends upon the position of the member 30, the operative position of which depends in turn upon the thickness of the work interposed between said member and the abutment 26. The beveling cutter will thus be maintained in the same operative relation to the face of the work, whatever the thickness of the work may be or however it may vary, so that the depth of the bevel will be constant. It will be clear also that adjustment of the screw 40 to vary the limit of movement of the presser member in the direction of the abutment 26 serves to vary to the same extent the limit of movement of the cutter 42 in the direction of the abutment, while adjustment of the screw 58 varies relatively the respective limits of movement of the cutter and the presser member and thereby serves to vary the normal depth of the bevel.

It will be clear that the scarfing or beveling mechanism may be readily attached to or detached from the machine and that it may be used or not as desired without affecting the operation of the machine as an edge trimming cutter. If it is desired to remove the beveling attachment the head 16 may be swung upwardly and the cutter 6 temporarily removed, after which the arm 48 may be detached from its pivotal support and the cutter 42, sleeve 44 and spring 46 removed endwise from the shaft. The cutter 6 may then be replaced and the head 16 secured in position, when the machine will operate solely as an edge trimming cutter. By a reversal of the above operations the attachment may be applied to the machine.

While it is possible to operate upon insoles satisfactorily on a machine constructed as above described, I find that both time and skill on the part of the operator are saved by providing the machine with a support for the last. The support preferably comprises a bracket arm 60 projecting from the frame 2, a block 62 pivotally mounted on the bracket 60 so as to swing in a substantially vertical plane to the extent permitted by a stop member 64 on the bracket, and an arm 66 pivotally mounted on the block 62 so as to swing in planes substantially at right angles to the plane of movement of the latter, the extent of movement being limited by a projection on the arm that engages in a recess 68 in the face of the block 62. The arm 66 may thus have a substantially universal movement. The arm 65 carries at its upper end a last supporting

pin 70 held loosely in a socket in the arm by means of a smaller pin 72, the mounting being such that the pin 70 may wabble in its socket, particularly in a direction transverse to the arm 66.

In the operation of the machine with the mechanism thus far described the workman slides upon the pin 70 a last having an insole attached thereto, and swings the last and support toward the cutters, guiding the last so that the lip 26 will be inserted between the insole and the last bottom and the portion of the side of the last close to the tread face will bear against the shoulder 24, thus inserting the insole between the lip 26 or abutment 26 and the member 30, which coöperate as presser members to hold the work in position for the action of the cutters. As the insole is inserted in the manner described the member 30 will yield to an extent depending upon the thickness of the insole, and will thereby adjust the cutter 42 to form a bevel of the predetermined depth depending upon the previous adjustment of the screw 58. In starting the cutting operation, the forepart of the last usually is raised to bring one side of the heel seat first into contact with the cutters, and the last is then swung forwardly and downwardly to present all portions of the edge of the heel seat to the action of the cutters. The mounting of the arm 66 and the pin 70 on the arm permit the movements of the last necessary to trim all parts of the insole that project at the sides of the heel as well as at the heel end, and to keep that portion of the side of the last that is directly adjacent to the tread face in contact with the shoulder 24, which is shaped to engage this portion and therefore to guide the sole with reference to the edge of the tread face. It is usually preferable to trim the edge of the insole so that the trimmed edge will lie flush with the lateral faces of the last. Consequently the guide member 22 should be suitably adjusted, as shown in Fig. 3, so that the edge of the sole when trimmed shall form practically a continuation of the contour of the side faces of the last. During the trimming operation the presser member 30 obviously will move in proportion to variations in the thickness of the insole, and will vary to the same extent the position of the cutter 42 so as to maintain a bevel of constant depth.

I have found that it is desirable to provide in a trimming machine of the type described further means to limit and determine the movement of the last when the insole is presented to the action of the cutter. An insole will frequently be wider than necessary at the shank or will be unevenly placed upon the last so as to project from the last farther than necessary at the shank portion. In such a case the workman may

turn the last so as to trim the edge farther than necessary toward the shank, and begin or end the trimming operation abruptly, thereby forming a ridge at the side of the sole where the trimming operation begins or where it ends. To obviate this tendency I have provided stops for limiting the turning movement of the last while in contact with the shoulder 24, which coöperate with the movable support to insure such other movement of the last as to cause the trimmed edge to merge gradually with the untrimmed edge at the shank. In the illustrated preferred embodiment these stops comprise projections 74 and 76 on a plate 78 that is adjustably mounted by a screw and slot connection on the face of the head 16 closely adjacent to the guide member 22. The member 22 and the plate 78 are so related as to be adjustable in paths that are substantially parallel. The stops 74 and 76 are thus in position to contact with the last on either side and limit the rearward movement of the forepart thereof when the last is mounted for turning movement upon the pin 70. If the workman begins the trimming on one side and ends it on the other side, as is usual, he will first bring the forepart of the last into contact with the stop 74 and then swing the heel portion together with the support in toward the cutter until the last contacts with the shoulder 24, thus giving the edge of the sole a slight longitudinal movement as it is brought into contact with the cutter. Similarly, at the completion of the trimming operation the last will contact with the stop 76 on the other side and cause the heel portion and support to swing away from the guide, thus withdrawing the sole edge from the action of the cutter while imparting thereto a slight movement longitudinally of its axis. The workman may, of course, begin the trimming operation at the rear of the heel and turn the last alternately in opposite directions until it contacts with the stops. The result in either case is to merge the trimmed edges gradually with the untrimmed portions. The plate 78, it will be understood, should be adjusted proportionally to the guide member 22, and it may be adjusted with respect thereto to vary the extent of the trimming operation.

While I have described my invention as embodied in a machine of specific construction it will be understood that this is merely for illustrative purposes and that the invention is susceptible of various other embodiments within the spirit and scope of the appended claims. It should also be understood that while I have employed frequently the term "beveling" in referring to the operation on the face of the insole, the invention is not limited to a cut of any particular character and the terms used are to

be construed broadly as referring to any form of cut that satisfies the purpose in view.

Having described my invention, what I claim as new and desire to secure by Letters Patent of the United States is:

1. A machine for operating upon an insole attached to the bottom of a last having, in combination, means for trimming the edge of the insole, means for beveling the margin of the bottom face of the insole, means for positioning the last and the insole to present the insole in operative relation to said trimming and beveling means, and means for variably controlling the relative positions of the insole and the beveling means so as to insure the formation of a bevel of constant depth. 75

2. A machine for operating upon an insole attached to the bottom of a last having, in combination, means for trimming the edge of the insole, means for beveling the margin of the bottom face of the insole, means for positioning the last and the insole to present the insole in operative relation to said trimming and beveling means, and means arranged to control by contact with the insole the position of the beveling means with reference to said last and insole positioning means. 90

3. A machine for operating upon an insole attached to the bottom of a last having, in combination, a cutter for trimming the edge of the insole, a cutter for beveling the margin of the bottom face of the insole, a guide upon which to position the last with the insole in operative relation to said cutters, the beveling cutter being adjustable toward and from said guide in directions transverse to the plane of the insole, and means for effecting said adjustment of the beveling cutter in accordance with the thickness of the insole presented. 105

4. A machine for operating upon an insole attached to the bottom of a last having, in combination, a cutter for trimming the edge of the insole, a cutter for beveling the margin of the bottom face of the insole, a guide upon which to position the last with the insole in operative relation to said cutters, said guide including means for supporting the insole on the side adjacent to the last, the beveling cutter being adjustable in directions toward and from said guide, a presser member arranged to contact yieldingly with the bottom face of the insole, and connections from said member to the beveling cutter for adjusting the position of said cutter in accordance with the thickness of the insole. 110

5. A machine of the class described having, in combination, a rotary edge trimming cutter, a second rotary cutter arranged to operate simultaneously therewith to bevel the work, an abutment or rest upon which to 130

position the work in operative relation to said cutters, and automatic means for varying the relative positions of said abutment and the beveling cutter so as to regulate the 5 depth of the bevel.

6. A machine of the class described having, in combination, a rotary edge trimming cutter, a second rotary cutter arranged to operate simultaneously therewith to bevel 10 the work, an abutment or rest upon which to position the work in operative relation to said cutters, and means for varying in proportion to the thickness of the work the relative positions of said abutment and the 15 beveling cutter so as to insure a bevel of constant depth.

7. A machine of the class described having, in combination, a rotary edge trimming cutter, a second rotary cutter arranged to 20 operate simultaneously therewith to bevel the work, an abutment or rest upon which to position the work in operative relation to said cutters, and means controlled by contact with the work for varying the relative 25 positions of said abutment and the beveling cutter.

8. A machine of the class described having, in combination, a rotary edge trimming cutter, a second rotary cutter arranged to 30 operate simultaneously therewith to bevel the work, an abutment or rest upon which to position the work in operative relation to said cutters, a presser member yieldably in contact with the work on the side opposite to said abutment, and connections for 35 effecting through movement of said member relative adjustment of said abutment and the beveling cutter.

9. A machine of the class described having, in combination, a rotary edge trimming cutter, a second rotary cutter arranged to 40 operate simultaneously therewith to bevel the work, coöoperating presser members between which to present the work in operative relation to said cutters, said members having provision for relative movement, and means for varying in proportion to said movement the position of the beveling cutter in relation to the work.

50 10. In a machine of the class described, the combination with a rotary edge trimming cutter, of a rotary scarfing or beveling cutter concentric therewith and arranged to operate simultaneously upon the work, said 55 cutters having provision for relative axial adjustment, means upon which to position the work in operative relation to said cutters, and means arranged to control by contact with the work the relative adjustment of said cutters.

60 11. In a machine of the class described, the combination with a rotary edge trimming cutter, of a rotary beveling cutter concentric therewith and arranged to operate simultaneously upon the work, the beveling 65

cutter being axially adjustable in relation to the edge trimming cutter, means upon which to position the work in predetermined relation to the edge trimming cutter, and automatic means for varying the relative 70 axial position of the beveling cutter in proportion to variations in the thickness of the work.

12. In a machine of the class described, the combination with a rotary edge trimming cutter formed with a series of cutting teeth, of a rotary beveling cutter concentric therewith and having teeth arranged to project between the teeth thereof, the beveling cutter being axially adjustable in relation 75 to the edge trimming cutter, means upon which to position the work in predetermined relation to the edge trimming cutter, a presser member arranged to contact yieldably with the work, and means to effect 80 axial adjustment of the beveling cutter in proportion to movement of said presser member toward or from the work.

13. In a machine of the class described, the combination with a rotary edge trimming cutter formed with a series of cutting teeth, of a rotary beveling cutter concentric therewith and having teeth arranged to project between the teeth thereof, the beveling cutter being axially adjustable in relation 95 to the edge trimming cutter, means for engaging one side of the work to determine the position thereof with reference to the edge trimming cutter, a presser member arranged to contact yieldably with the opposite side of the work, and means whereby the axial position of the beveling cutter is determined by the position of said presser member.

14. In a machine of the class described, the combination with a rotary edge trimming cutter formed with a series of cutting teeth, of a rotary beveling cutter concentric therewith and having teeth arranged to project between the teeth thereof, the beveling 105 cutter being axially adjustable in relation to the edge trimming cutter, means upon which to position the work in operative relation to said cutters, a presser member arranged to contact with the work upon the 110 same side as the beveling cutter, means to hold the presser member and the beveling cutter yieldably in contact with the work, and means whereby the limit of operative movement of the beveling cutter toward the 115 work is determined by the position of the presser member.

15. In a machine of the class described, the combination with a rotary edge trimming cutter, of a rotary beveling cutter concentric therewith and arranged to operate simultaneously upon the work, means upon which to position the work in operative relation to said cutters, a presser member arranged to contact with the work upon the 120 125 130

same side as the beveling cutter, means whereby the beveling cutter and the presser member are held in predetermined relative positions in contact with the work, and 5 means for varying the normal relative positions of said cutter and presser member.

16. In a machine of the class described, the combination with a rotary edge trimming cutter, of a rotary beveling cutter concentric therewith and arranged to operate simultaneously upon the work, the beveling cutter being axially adjustable in relation to the edge trimming cutter, an abutment or rest upon which to position the work 15 in operative relation to said cutters, a presser member arranged to contact with the work upon the same side as the beveling cutter, means tending to force said beveling cutter and presser member toward their 20 respective limits of movement in the direction of said abutment, and means for varying said limits of movement of the cutter and presser member without disturbing their relative positions.

25 17. In a machine of the class described, the combination with a rotary edge trimming cutter, of a rotary beveling cutter concentric therewith and arranged to operate simultaneously upon the work, the beveling cutter being axially adjustable in relation to the edge trimming cutter, an abutment or rest upon which to position the work 30 in operative relation to said cutters, a presser member arranged to contact with the work upon the same side as the beveling cutter, means tending to force said beveling cutter and presser member toward their 35 respective limits of movement in the direction of said abutment and to hold them in predetermined relative positions while in contact 40 with the work, means for varying the normal relative positions of said cutter and presser member, and means for varying said limits of movement of the cutter and presser 45 member without disturbing their relative positions.

18. A beveling machine comprising, in combination, a rotary shaft, a beveling cutter mounted thereon, means adjacent to the 50 cutter upon which to position the work, a presser member arranged to contact yieldingly with the work and coöperating with said positioning means to hold the work in operative relation to the cutter, and means 55 operatively connected with said presser member for adjusting the cutter axially on the shaft in proportion to variations in the thickness of the work.

19. A beveling machine comprising, in 60 combination, a rotary shaft, a beveling cutter axially movable upon the shaft, means to hold said cutter yieldably in engagement with the work, a presser member arranged to contact with the work on the same side as

the beveling cutter and movable toward and 65 from the work, a spring pressed plunger for holding the presser member yieldably in contact with the work, and means connected with the beveling cutter and engaging 70 said plunger to limit and control the position of said cutter with reference to the work.

20. A beveling machine comprising, in combination, a rotary shaft, a beveling cutter axially movable upon the shaft, means 75 to hold said cutter yieldably in engagement with the work, a presser member arranged to contact with the work on the same side as the beveling cutter and movable toward and from the work, a spring pressed plunger for 80 holding the presser member yieldably in contact with the work, an adjustable stop member for varying the limit of movement of the presser member in the direction of the work, and means connected with the beveling cutter 85 and engaging said plunger to limit and control the position of said cutter with reference to the work.

21. A beveling machine comprising, in combination, a rotary shaft, a beveling cutter axially movable upon the shaft, means to hold said cutter yieldably in engagement with the work, a presser member arranged to contact with the work on the same side as the beveling cutter and movable toward and 90 from the work, a spring pressed plunger for holding the presser member yieldably in contact with the work, and means connected with the beveling cutter and engaging said 95 plunger to limit and control the position of 100 said cutter with reference to the work, said means including provision for varying the normal position of said cutter with reference to the presser member.

22. A beveling machine comprising, in 105 combination, a rotary shaft, a beveling cutter axially adjustable on said shaft, means to hold the cutter yieldably in engagement with the work, a presser member arranged to contact with the work on the same side 110 as the beveling cutter and movable toward and from the work, a spring pressed plunger for holding the presser member yieldably in contact with the work, a sleeve loosely mounted on the shaft and connected with 115 the cutter, an arm pivoted on the frame of the machine and connected to operate said sleeve, said arm having an extension positioned opposite the end of said plunger and a screw threaded in said extension and engaging said plunger.

23. In a machine of the class described, the combination with a rotary shaft and an edge trimming cutter mounted thereon, of a beveling cutter axially adjustable on the 125 shaft, a head pivoted on the frame of the machine to swing in a plane substantially parallel to the cutter shaft and carrying

guiding means to determine the position of the work in relation to the cutters, means to secure the head in fixed operative position with the guiding means adjacent to the 5 edge trimming cutter, a presser member arranged to contact with the work on the same side as the beveling cutter and movable toward and from the work, a spring pressed plunger for holding the presser member 10 yieldably in contact with the work, an arm mounted to swing from the pivotal point of said head and connected to adjust the beveling cutter axially on the shaft, and means carried by said arm and engaging the 15 plunger to limit the movement of the cutter toward the work.

24. A machine for trimming an insole attached to the bottom of a last having, in combination, a cutter, a guide member 20 upon which to position the side surfaces of the last as the latter is moved to present different portions of the insole to the action of the cutter, said guide member being arranged to maintain a stationary relation to 25 the cutter during the trimming operation, and means for limiting movement of the forepart of the last toward the rear of the machine without preventing other movement of the last with respect to the guide 30 member at the beginning or end of the trimming operation near the shank.

25. A machine for trimming an insole attached to the bottom of a last having, in combination, a rotary cutter, a guide member 35 upon which to position the side surfaces of the last as the latter is turned to present different portions of the insole to the action of the cutter, said guide member being formed to permit longitudinal movement of 40 the last with reference thereto when the cutter is operating upon the sides of the insole near the shank, and means for limiting said turning movement of the last while in contact with the guide member without preventing such longitudinal movement of the 45 last with respect to the guide member and the cutter.

26. A machine for trimming an insole attached to the bottom of a last having, in 50 combination, a rotary cutter, a stationary guide member upon which to position the side surfaces of the last as the latter is turned to present different portions of the insole to the action of the cutter, a loosely 55 mounted support upon which to position the last for turning movement in contact with the guide member, and stationary means for limiting said turning movement of the last while in contact with the guide member 60 without preventing other movement of the

last and support with respect to the guide member and the cutter.

27. A machine for trimming an insole attached to the bottom of a last having, in combination, a rotary cutter, a guide member 65 upon which to position the side surfaces of the last as the latter is turned to present different portions of the insole to the action of the cutter, a support upon which to position the heel end of the last for turning 70 movement, said support being movable to carry the heel end of the last toward and from the cutter and the guide member in a path substantially parallel to the plane of the cutter, and stops upon which to position that part of the last forward of the heel as the support is moved toward or from the cutter, whereby to impart to the last and insole a slight longitudinal movement at the beginning or end of the trimming operation 75 near the shank.

28. A machine for trimming an insole attached to the bottom of a last having, in combination, a rotary cutter, a guide member 80 upon which to position the side surfaces of the last as the latter is turned to present the insole to the action of the cutter, said guide member being adjustable to vary the distance of the work from the axis of the cutter, and a member mounted closely adjacent to said guide and having means suitably located to limit the turning movement of the last while in contact with the guide, said member being adjustable to control the extent of said turning movement. 95

29. A machine for trimming an insole attached to the bottom of a last comprising a driven cutter, means for engaging the sides of the last to position it relatively to the cutter as it is moved to present different 100 portions of the insole to the operation of the cutter, means arranged to extend between the bottom of the last and the insole, means located opposite to said last mentioned means to engage the outer face of the insole 105 at a point close to the point of operation of the cutter to prevent the insole from bending away from the cutter, a second cutter for beveling the margin of the outer face of the insole, and connections between said 110 insole engaging means and the second cutter for controlling the position of said cutter with reference to the work.

In testimony whereof I have signed my name to this specification in the presence of 115 two subscribing witnesses:

EUGENE L. KEYES.
